United States Patent Office

Des. 213,774
Patented Apr. 8, 1969

213,774

SOFA

Robert A. Gera, Glencoe, Ill., assignor to Schnadig Corporation, Chicago, Ill., a corporation of Delaware

Filed Mar. 14, 1968, Ser. No. 10,982

Term of patent 14 years

Int. Cl. D6—01

U.S. Cl. D15—11

The figure is a perspective view of a sofa showing my design.

The end not shown is like the end shown while the back is conventional.

I claim:

The ornamental design for a sofa, as shown and described.
